UNITED STATES PATENT OFFICE.

WILLIAM R. DUNHAM, OF WEBB CITY, MISSOURI.

IMAGE-PROJECTING MACHINE.

1,178,786.

Specification of Letters Patent. Patented Apr. 11, 1916.

Application filed June 17, 1915. Serial No. 34,730.

To all whom it may concern:

Be it known that I, WILLIAM R. DUNHAM, a citizen of the United States, residing at Webb City, in the county of Jasper and 5 State of Missouri, have invented certain new and useful Improvements in Image-Projecting Machines; and I do declare the following to be a full, clear, and exact description of the invention, such as will enable others skilled in the art to which it appertains to make and use the same.

My invention relates broadly to the class of optics and more particularly to image projecting machines designed primarily for 15 the projecting of advertisements upon suitable screens.

The main object of the invention is to provide a machine of this class which will not only be very efficient in operation, but 20 which may be easily and inexpensively manufactured.

To the above end, a further object lies in the provision of construction whereby certain adjustments may be made for allowing 25 more or less advertisements to be displayed.

Yet another object is to construct the device in such a manner as to allow the projecting light and the lens in advance thereof to retain the same relative relation in re- 30 spect to the images, regardless of the amount of adjustment made.

With the foregoing and numerous minor 35 objects in view, the invention resides in certain novel features of construction and combination herein described and claimed. In describing the invention I shall refer to the accompanying drawings wherein like reference characters designate corresponding parts throughout the various views and 40 wherein:

Figure 1 is a side elevation of a projecting machine constructed in accordance with my invention; Fig. 2 is a top plan view thereof; Fig. 3 is a rear end view; Fig. 4 45 is a vertical transverse section as seen along the plane designated by the line 4-4 of Fig. 1; and, Fig. 5 is a diagrammatic perspective view illustrating more particularly the intermittent feed mechanism for successively 50 advancing the numerous advertisements, and the commutator for intermittently illuminating the projecting light.

In these figures, constituting a part of the application, 1 designates a horizontal elongated base which may be of any preferred design. Secured to the intermediate edge portions of the base 1, upon the upper side thereof, is a pair of longitudinally disposed tracks 2, which are here shown of dove tail formation in transverse section. 55 Rising from the base 1 at the rear ends of the tracks 2, is a pair of fixed rear standards 3 whose tops are connected by a transverse bar 4, while their lower ends are preferably provided with slides 5 clamped upon the 60 rear ends of the tracks 2 by set screws 6 or the equivalent thereof.

Extending forwardly from the upper ends of the two standards 3 and secured thereto in any appropriate manner, is an upper pair 70 of tracks 7 which lie parallel to and are of a length equal to the tracks 2, the front ends of said tracks 7 being preferably provided with longitudinal slots 8 as disclosed in Figs. 1 and 4. Contacting with the outer sides of the tracks 7 and having clamping bolts 9 passing through the slots 8 thereof, is a front pair of movable standards 10, the lower ends of said standards being equipped with slides 11 which are movable longitudinally upon the tracks 2 and which may be locked in adjusted position on said tracks by the provision of set screws 12 or the equivalent thereof.

The rear fixed standards 3 are provided on their rear sides with upper bearings 13 and lower bearings 14, the former revolvably supporting a shaft upon which right and left guide sprockets 15 are secured, while the latter are provided to rotatably support right and left driving sprockets 16, one of which is provided with a plurality of laterally extending studs or projections 17 designed for a purpose yet to be described. Immediately in advance of the bearings 13, the front movable standards 10 are provided with bearings 18 in which an upper shaft having right and left guide sprockets 19 is revolvably mounted while below the bearings 18 and in advance of the bearings 14, said front standards 10 are equipped with additional bearings 20 in which the shaft of lower right and left guide sprockets 21 is revolvably mounted.

Passing around the two driving sprockets 16, and around the guide sprockets 13, 19 and 21, is a pair of endless elements 22, herein shown in the form of sprocket chains which may be lengthened or shortened in any well known manner to support the desired number of panel receptacles 23 which are pivotally supported therebetween and in which transparent panels 24, containing the advertising matter to be displayed upon the screen, are removably mounted in any appropriate manner. It will be noted that the receptacles 23 are so supported upon the chains as to allow them to always assume an upright position, this being essential in order that rays of light may be successively projected through the individual panels as they travel in advance of light projecting means now to be described.

The aforesaid projecting means comprises an electric light 25 which is mounted on a light bracket 26 carried by the front movable standards 10; a lens 27 likewise carried by said standards and disposed immediately in advance of the light 25, but in rear of the front upright series of panels 24; and an additional and longitudinally adjustable lens support 28 which is carried by an upright 29 rising from the front end of the base 1, said support 28 being equipped with any preferred types of lenses, for accomplishing the best results. It is to be observed that regardless of the positioning of the front standards 10 in respect to the rear standards 3, the front series of panels, the lenses 27, and the light 25, will always assume the same relative positions, this being a salient feature of the invention.

Operating in conjunction with the construction so far described, is means for intermittently advancing the two chains 22 and the panels carried thereby, to successively position the latter in advance of the lenses 27, and additional means for intermittently illuminating the light 25, it being understood that the latter is flashed after each individual panel is moved to the proper position in respect thereto. For so advancing the chains 22, a slowly rotated driving shaft 30 is positioned transversely in rear of the rear standards 3 and is provided with a laterally extending arm 31 which projects into the rotary path of the projections 17 on the left hand sprocket 16, whereupon each revolution of the shaft 30 will rotate the two gears 16 a predetermined portion of a revolution, thus intermittently advancing the chains 22 and the advertising panels carried thereby.

Secured to the driven shaft 30 is a commutator 32 which comprises an insulating ring 33 surrounding said shaft and in turn partially surrounded by a split contact ring 34, the gap of this ring being filled by insulating material extending from the ring

33 as clearly disclosed in Fig. 5. Disposed for contact with the periphery of the contact ring 34, is a brush 35 from which a current conducting wire 36 leads to a battery 37 or other appropriate source of current supply, an additional wire 38 being shown as leading from said battery to one terminal of the light 25, while yet another wire 39 continues from the opposite terminal of said light and is electrically connected in any preferred manner to the ring 34. By this construction, the insulation in the gap between the ends of the split ring 34, will contact with the brush 35 while the arm 31 is advancing the chains 22 to position one of the panels 24 in advance of the light 25, but the moment this advancing is completed, one end of the split ring 34 comes in contact with the brush 35, thus instantly completing the circuit of the light 25 and advancing the latter. The result is that the image imprinted upon the panel being displayed, is projected through the lenses in the support 28, upon any appropriate type of screen (not shown).

It will be understood that any preferred means may be provided for slowly rotating the driving shaft 30, although in the drawings appropriate speed reducing gearing 40 is shown for this purpose, said gearing being driven by a worm and worm gear 41 from an electric motor 42.

From the foregoing description, taken in connection with the accompanying drawings, it will be evident that although comparatively simple construction has been provided for carrying out the objects of the invention, the complete machine will be very efficient in operation. Particular emphasis is laid upon the construction for allowing the chains 22 to be lengthened or shortened for the purpose of carrying more or less advertising panels, due consideration being directed to the fact that the lens 27, and the light 25 are movable with the standards 10, while the lens support or carrier 28 is adjustable longitudinally within the guide carried by the upper end of the standard 29. Needless to say, these are very salient features of the invention and perform their functions to great advantage.

Although the type of feed mechanism described and shown is preferable, as is likewise the style of circuit closer and breaker, it will be evident that these devices could well be embodied in other forms.

I claim:

1. A projecting machine comprising a rigid rear supporting member having a guide, a movable front supporting member in advance of the rear member and adjustable toward and away therefrom, upper and lower guides carried by said movable front member, and intermittently actuated light projecting means carried by the movable

supporting member, combined with an intermittently advanced endless element passing around the several guides, and transparent panels carried by said element and traveling in advance of the light projecting means.

2. A projecting machine comprising a rigid rear supporting member having a guide, a movable front supporting member in advance of the rear member and having upper and lower guides, a lens carried by the movable supporting member, intermittently actuated light projecting means, in rear of said lens, combined with an intermittently advanced endless element passing around the several guides, and transparent panels carried by said endless element and traveling in advance of the lens.

3. A projecting machine comprising a rigid rear supporting member having a guide, a movable front supporting member in advance of the rear member and having upper and lower guides, a lens carried by the movable supporting member, and intermittently actuated light projecting means likewise carried by said movable member and disposed in rear of the lens, combined with an intermittently advanced endless element passing around the several guides, and transparent panels carried by said endless elements and traveling in advance of the lens.

4. A projecting machine comprising a base, a rigid rear standard rising therefrom, a lower track in advance of the rear standard, an upper track projecting forwardly from the upper end of the same, a movable front standard whose upper and lower ends are slidably engaged with the upper and lower tracks, releasable means locking said front standard against movement, and front and rear guides carried by the front and rear standards, combined with an intermittently advanced endless element passing around the front and rear guides, transparent panels carried by the endless element, and intermittently actuated light projecting means in advance of which the panels travel.

5. A projecting machine comprising electrically operated light projecting means, and a plurality of transparent panels traveling in advance of said means, combined with a movable panel advancing wheel having a plurality of circumferentially spaced projections, a rotated driving shaft, a laterally projecting arm thereon disposed in the path of the projections, a commutator carried by the shaft, a brush bearing on said commutator and an electric circuit including the light projecting means, the commutator and the brush.

6. A projecting machine comprising a base, a pair of spaced upright standards rising therefrom, a pair of parallel tracks extending forwardly from the standards and carried by the base, an additional pair of

spaced upright standards having slides shiftable longitudinally on the tracks, a lamp bracket rigidly connecting the additional upright standards, guides carried by the two pairs of standards, a flexible endless member trained around said guides and carrying a number of transparent panels, a lamp carried by the lamp bracket, and means for advancing the endless member to successively dispose the panels in advance of the lamp.

7. A projecting machine comprising a base, a pair of spaced upright standards rising therefrom, a pair of parallel undercut tracks extending forwardly from the standards and carried by the base, a pair of slides snugly engaging the undercut tracks and movable longitudinally thereon, means for normally preventing movement of the slides, an additional pair of upright standards rising from the slides, guides carried by the two pairs of standards, an endless member trained around said guides and carrying a number of transparent panels, a source of light, and means for intermittently advancing the endless member to successively dispose the panels in advance of said source of light.

8. A projecting machine comprising a base, a pair of spaced upright standards rising therefrom, a pair of horizontal parallel tracks on the base and extending forwardly from the lower ends of said standards, an additional pair of spaced horizontal tracks extending forwardly from the upper ends of said standards and having longitudinally slotted front extremities, an additional pair of upright standards having slides movable longitudinally on the first-named tracks and having their upper ends disposed adjacent the slotted terminals of the additional tracks, clamping bolts passing through said upper ends of the additional standards and through the slots of said terminals, and means for normally preventing movement of the slides on their respective tracks, combined with guides carried by the two pairs of standards, an endless member passing around said guides and carrying a number of transparent panels, a source of light, and means for intermittently advancing the endless member to successively dispose the panels in advance of said source of light.

9. A projecting machine comprising a base, a pair of parallel horizontal tracks carried thereby, a rear pair of slides on said tracks and means for normally preventing movement thereof, a rear pair of upright standards rising from the rear slides, a front pair of upright standards rising from the front slides, additional horizontal tracks secured to one pair of standards and having sliding connections with the other pair, guides carried by the two pairs of standards, a flexible member trained around said guides

1,178,786

and carrying a plurality of transparent panels, a source of light, and means for intermittently advancing said member to successively dispose the panels in advance of 5 said source of light.

In testimony whereof I have hereunto set

my hand in presence of two subscribing witnesses.
